UNITED STATES PATENT OFFICE

LUDWIG F. ZORC, OF CHICAGO, ILLINOIS

DESIGN FOR A RADIATOR SHELL

Application filed July 3, 1931. Serial No. 40,406. Term of patent 3½ years.

To all whom it may concern:

Be it known that I, LUDWIG F. ZORC, a citizen of the United States, residing at Chicago, in the county of Cook and State of Illinois, have invented a new, original, and ornamental Design for a Radiator Shell, of which the following is a specification, reference being had to the accompanying drawings, forming part thereof.

Figure 1 is a front elevation of the radiator shell showing my new design.

Figure 2 is a side elevation thereof.

I claim:—

The ornamental design for a radiator shell as shown.

LUDWIG F. ZORC.
